TRAY ATTACHMENT FOR A GOLF CART
OR SIMILAR ARTICLE

Harold W. Nash, Los Angeles, Calif.

Application January 11, 1955, Serial No. 33,922

Term of patent 14 years

(Cl. D34—5)

Fig. 1 is a perspective view of the tray attachment for a golf cart or similar article, showing my new design;

Fig. 2 is a side elevational view thereof; and

Fig. 3 is an end elevational view thereof.

I claim:

The ornamental design for a tray attachment for a golf cart or similar article, substantially as shown.
